CLAIM

The ornamental design for a notebook computer, as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the notebook computer in an open state;

FIG. 10 is another perspective view thereof;

FIG. 11 is a left side view thereof;

FIG. 12 is a top view thereof; and,

FIG. 13 is a cross-sectional view taken along line 13-13 in FIG. 12.

The dashed broken lines illustrate portions of the notebook computer that form no part of the claimed design. The long dash short dash broken lines represent the boundaries of the claimed design and form no part thereof.

1 Claim, 10 Drawing Sheets
